(57) CLAIM

The ornamental design for a shoe attachable brush, as shown and described.

DESCRIPTION

FIG. 1 is a right side elevation view of a shoe attachable brush showing my new design, the opposite side being a mirror image of the shown;

FIG. 2 is a rear elevation view thereof;

FIG. 3 is front elevation elevation view thereof;

FIG. 4 is a top plan view thereof; and,

FIG. 5 is a bottom plan view thereof.

The broken lines in FIG. 1 of the drawings depict a shoe as environmental subject matter only and form no part of the claimed design.
